RAILWAY TRAFFIC CONTROLLING APPARATUS

Ralph R. Kemmerer, Swissvale, Pa., and Howell N. Dixon, Hamlet, N. C., assignors to The Union Switch & Signal Company, Swissvale, Pa., a corporation of Pennsylvania

Application September 15, 1938, Serial No. 230,083

15 Claims. (Cl. 246—34)

Our invention relates to railway traffic controlling apparatus and more specifically to apparatus for stopping the operation of highway crossing signals, operating detector locking track sections, as well as for clearing out detector track sections generally in signalling systems employing one form of track circuit current, such as coded current, for the control of wayside and cab signals, and another form of track circuit current, such as uncoded current, for clearing out the highway crossing signals or other detection apparatus.

One feature of our invention is the provision of apparatus of the above character in which the code following track relay which controls the usual wayside signals is not required to perform the clearing out operation for the highway crossing signals, the latter function being performed by other apparatus selectively responsive to the uncoded energy which is provided for the purpose of signal clearing or track circuit detection. In this manner, the danger of improper signal operation due to an accidental failure of the code following track relay to operate is diminished and the safety factor of the system as a whole is increased.

We shall describe one form of railway traffic controlling apparatus embodying our invention and shall then point out the novel features thereof in claims.

In the accompanying drawings, Figs. 1a and 1b when placed end to end with Fig. 1b at the right are a diagrammatic view of a stretch of railway track showing apparatus embodying our invention as applied to the clearing out of a pair of highway crossing cut sections upon the passage of a train.

Similar reference characters refer to similar parts in each of the two views.

In coded wayside and cab signalling systems which include the control of highway crossing apparatus or require the performance of other track detection functions it is desirable that the current which is used for clearing out the highway crossing apparatus be of such character as to perform the desired wayside control functions without at the same time interfering with the proper operation of the usual wayside and cab signals. These should, of course, not respond to the presence of such control or detection current in the rails. One manner in which this selective operation can be obtained is by using coded current for the control of the wayside and cab signals and using uncoded or so-called "steady" energy for the control of the highway crossing or other detection apparatus. By making use of uncoded or steady energy in the rails, a distinctive response of certain auxiliary apparatus can be obtained which response can be used for the selective control of the highway crossing or other

apparatus without at the same time causing an undesired response of the cab or wayside signals. These, as is well known, will usually require the presence of coded impulses in the rails before operation of the wayside decoder will take place or before an operating voltage will be transmitted to the cab signalling apparatus.

One advantage of coded wayside signalling systems over systems of the usual steadily energized track circuit type is that the former systems provide a high degree of foreign current protection. Where steady energy is used for the clearing out of highway crossing apparatus, however, the code following track relay is ordinarily incapable of distinguishing between the presence of such steady energy and the presence of some foreign current which may have entered the track system. Accordingly, if the steadily energized condition of the code following track relay itself is used for the purpose of providing highway crossing control, a certain amount of foreign current protection may be lost thereby. Moreover, the design of the usual code following track relay is such that it is considered a safety type relay only when performing a code following or dynamic function in contrast with a steadily energized or static function in which its front contacts remain constantly closed.

Our apparatus disclosed herein is directed to overcoming the above disadvantages and we accomplish this result by providing apparatus which is separate and apart from the code following track relay itself and which responds selectively to the presence of steady energy in the rails for the purposes herein set forth without in any manner interfering with the proper operation of the remaining apparatus.

Referring now to Figs. 1a and 1b of the drawings, we have shown herein a stretch of railway track comprising two complete block sections A—C and C—F. These block sections are subdivided by means of insulated joints at locations B, D, and E into track circuit sections 4T, A4T, 6T, A6T, and B6T, respectively. These track circuit sections are necessary for the proper control of highway crossing apparatus at locations D and E. Traffic in the stretch A—F normally moves from left to right in the direction of the arrow, entering traffic being controlled by the wayside signal 4 and leaving traffic being controlled by another wayside signal 8.

Each track circuit is provided with a code following track relay designated by the reference character TR with a suffix corresponding to the location. As shown, these code following relays are of the two-element alternating current type having a control element 3 energized from the track and a local element 5 which is locally energized. The energy received by these track relays is supplied from a suitable track transformer T.

located at the other end of the track circuit, the primary of which is energized from a source of alternating or other periodic current, not shown, having the terminals BX-CX. Interposed between those of the track transformers which are supplied with energy over line wires are suitable insulating transformers IT. These insulating transformers are for the purpose of reducing exposure of the line wires to high tension lines and other lines paralleling the track so as to avoid undesired capacity and inductive interference from such lines.

As determined by the condition of traffic in advance of the blocks A-C and C-F, the source of current for the respective track transformers may be coded at a rate of either 180 or 80 times per minute by suitable code transmitters CT at locations C and F. In the embodiment which is illustrated, these code transmitters are of the constantly operating type. Provision is also made for supplying steady or uncoded energy to the track circuits 6T and A6T for the purpose of clearing out or stopping the operation of the highway crossing signals 6X and A6X in a manner to be set forth in detail hereinafter. The highway crossing signals 6X and A6X are controlled by suitable governing relays XRD and XRE, respectively. Since the control circuits which connect these relays with the usual control apparatus for operating the signals are well known, these circuits are not shown in the drawings in order to simplify the disclosure.

The cut section location B is a starting point for the control of highway crossing signals 6X. Similarly, the signal location C is a starting point for the control of the highway crossing signals A6X. For the purpose of controlling these highway crossing signals, the track circuits 6T and A6T are each provided with an auxiliary track relay ATRC and ATRD, respectively, the particular functions of which will be described in detail hereinafter. Since there are no further highway crossing locations in the block C-F beyond location E, the track circuit B6T is provided only with the usual code following track relay without a corresponding auxiliary track relay. Track circuits 4T and A4T both receive coded energy from the signal location C and similarly, track circuits 6T, A6T, and B6T all receive coded energy from the signal location F. This coded energy is, of course, repeated over contacts of the track relay at the respective locations B, D, and E into the corresponding track circuits in the rear thereof. The uncoded energy for track circuits 6T and A6T is, however, not repeated from locations in advance but is supplied locally at the locations D and E, respectively.

We shall first describe the operation of the individual apparatus at certain of the locations within the blocks A-C and C-F and shall then describe more fully the sequence of events as a train passes through the stretch A-F in which these two blocks are included.

Looking first at location C, the auxiliary track relay ATRC is an alternating current relay which may be of any suitable type but is preferably of the polarity responsive type. Since this relay is required to respond to steady energy only, it need not be of the code following design. As shown, the auxiliary track relay is of the two-element type having a control element 7 which is connected in multiple with the control element 3 of the track relay TRC and having a local element 9 which is energized locally from a suitable source of alternating current having the termi-

nals BX-CX. It will be noted that the connections of winding 9 of relay ATRC are such that the relative instantaneous polarity of this element is opposite to that of the element 5 of track relay TRC whereas elements 7 and 3 are of like instantaneous polarity. With these connections, the auxiliary relay will respond only to current of opposite instantaneous polarity as compared with that to which the track relay TRC will respond. Accordingly, the coded energy which is supplied to the track relay TRC will drive the auxiliary relay against its backstop (at such time as local winding 9 is energized) to hold this relay in its deenergized position. Also, the uncoded energy of opposite instantaneous polarity which is supplied for operating the auxiliary relay will not produce a pick-up operation of the track relay TRC. Obviously, relays ATRC and TRC could be of the polarized direct current type and be operated from direct current instead of alternating current track circuits. Moreover, the polarized feature of these relays can be dispensed with, if desired, provided that relay TRC is of the code following type and relay ATRC is of the non-code following type, but when this is done the safety factor of the system will be reduced somewhat.

The decoding unit DUC is of the usual and well-known type and for this reason has not been shown in detail in order to simplify the disclosure. This unit usually comprises a transformer the primary of which is supplied with direct current periodically reversed at code frequency so as to produce an alternating current output of corresponding frequency in the secondary winding 35 of the transformer which output, in turn, energizes the decoding relays HC and DC through suitable rectifiers forming a part of the decoding unit. To explain this operation more fully, when the track relay TRC is following code, it supplies 40 this periodically reversed energization to the input circuit of the decoding unit DUC over its contacts 10-11 and 10-12 from a suitable source of direct current having the terminals B-C. The decoding relay DC is suitably tuned by 45 means of reactance and capacity (not shown) in well-known manner whereby it will respond only when the track relay is following 180 code, that is, when the decoding unit DUC is delivering an output of 180 code. The circuit of relay HC is 50 untuned so that this relay will operate both when the received code is 180 and also when it is 80.

The code received by the track relay TRC will be 180 when the block in advance of location F is unoccupied and will be 80 when this advance 55 block is occupied by a train. When either of the track circuits A6T or B6T is occupied, the track relay ATRC will receive uncoded energy as will appear more fully hereinafter. It will be noted that the energy for the local element 9 of auxiliary relay ATRC is carried over a back contact 13 of the decoding relay HC so that when code is received in the track circuit 6T, the auxiliary relay ATRC will not be subjected to a hammering action against its backstop, thus eliminating 60 excessive wear due to this cause.

Looking next at location B, there are provided at this location two slow release repeating relays TPB and ATPB which provide a check on the code following action of the track relay TRB. 70 Relay TPB checks that the front contact 14-15 of relay TRB is being periodically closed at code intervals and relay ATPB checks that the back contact 14-16 of this relay is being periodically closed at code intervals and that relay TPB is 75

energized. The circuit for relay TPB is obvious and the circuit for relay ATPB is carried over the front contact 47 of relay TPB and the back contact 44-46 of relay TRB. A similar check is provided at the cut section locations D and E. The repeating relays TP and ATP control the supply of code to the sections in the rear thereof and prevent such code from being supplied if 5 the track relay should for any reason cease to follow code.

We shall next describe the manner in which energy is fed to the various track circuits with the apparatus occupying the condition in which 15 it is illustrated in the drawings. Then we shall assume a train passing along the track from left to right, entering and leaving each track circuit and shall show the means whereby proper operation of the crossing signals is obtained 20 during the progress of the train through the section.

As previous pointed out, the track circuits in the block C-F receive alternating current from a suitable source BX-CX which is coded over 25 one or another of the contacts 180 and 80 operated by the code transmitter CTF at location F, depending upon traffic conditions in advance. These contacts may be operated by any suitable 30 apparatus such, for example, as a motor device to periodically open and close at certain predetermined frequencies such as 180 and 80 times per minute. Contact 180 operates at the former frequency to transmit the clear or unoccupied code, whereas contact 80 operates at the latter 35 frequency and transmits the caution code to the track circuits of block C-F. The particular code frequency transmitted is dependent upon traffic conditions in advance which, in turn, are reflected by the position of the decoding relays 40 HF and DF.

In the particular embodiment which we have shown at location F, the decoding relay DF which is responsive only to 180 code does not enter into the control of the code which is supplied to the sections in the rear but is instrumental in governing the operation of the wayside signal 8. The control circuits for this wayside signal are well known and so have not been shown in order to simplify the disclosure as much as possible. 45 Obviously, our apparatus is not limited to two codes only, or to any particular codes such as 180 and 80, but may be used as well with additional codes which may have different frequencies as well as with codes of a different type such, for 50 example, as the time code or count code.

As shown in the drawings, the track transformer TF for track circuit B6T receives energy of 180 code from one terminal BX of the source over the 180 contact of code transmitter CTF, 55 front contact 18-19 of decoding relay HF and wires 21 and 22, to the primary winding of the track transformer and the other terminal CX of the source. This coded energy is also supplied over a branch circuit including wire 23 to the primary winding of the insulating transformer ITF which, in turn, supplies this energy from its secondary winding over the line wires and front contacts 24 and 25 of relay TPE as well as front contacts 26-27 and 28-29 of relay ATPB to the 60 primary winding of the track transformer TE. Another branch of this line wire circuit carries the 180 code to the primary winding of track transformer TD over front contacts 32 and 33 of relay ATPB, front contacts 34 and 35 of relay 65 TPD, and front contacts 36-37 and 39-40 of

relay ATPD. It is seen, therefore, that each of the track circuits 6T, A6T, and B6T receives 180 code from the code transmitter CTF at location F. The particular code frequency is, of course, dependent upon the traffic conditions ahead, as 5 reflected by the condition of the decoding apparatus at location F.

In a similar manner, the track circuits 4T and A4T receive coded energy from the code transmitter CTC at location C, the particular code 10 frequency of which depends upon the traffic conditions in advance of location C. Since the track circuits 6T and A6T are the only ones which receive steady energy, the auxiliary track relays are required for these track circuits only. 15

Having described the operation of the individual apparatus, we shall now describe the operation which takes place when a train passes through the blocks A-C and C-F from left to right. 20

When a train enters the track circuit 4T, the track relay TRA will be shunted and will cause the signal 4 to be placed at "stop" in the usual and well-known manner which need not be described in detail. Location B is the starting 25 point for initiating operation of the crossing signals 6X and when the train enters the track circuit A6T it will shunt the track relay TRB and so will deenergize the repeater relays TPB and ATPB. With the deenergization of the track 30 relay TRB, coded energy which was fed to track circuit 4T will be interrupted at the front contacts 42 and 43 of the repeater relays ATPB. Accordingly, signal 4 will continue to be held at "stop" even though the train passes completely 35 out of the track circuit 4T.

The highway crossing control relay XRD is normally energized from a suitable source having the terminals BX-CX over a circuit which includes the front contacts 44 and 45 of relay 40 ATPB and the front contacts 46 and 47 of relay HC. Upon the release of relay TRB, followed by the release of relay ATPB, the front contacts 44 and 45 of the latter relay will open and so will deenergize the relay XRD which, in closing 45 its back contact 48, will initiate the operation of the highway crossing apparatus at location D.

When the train enters the track circuit 6T, the track relay TRC will become deenergized and will, in turn, cause the decoding relays HC and DC to 50 release so as to cause the signal 6 to display its "stop" indication. With the deenergization of relay HC, the front contacts 46 and 47 of this relay will be open so as to retain the highway crossing control relay XRD in its deenergized position and thus to maintain the highway crossing 55 signals 6X in their operated condition. The deenergization of relay HC will also cause 80 code to be fed by code transmitter CTC over the back contact 49-51 of relay HC to the primary winding of track transformer TC. Concurrently, this code will also be fed to the insulating transformer ITF but whether track circuit 4T will receive this code or not will depend upon whether the train has completely vacated the section 60 65 B-C. Once the track circuit A4T is vacated, the track relay TRB will follow 80 code and so will energize the repeater relay ATPB which, in turn, will close its front contacts 42 and 43 so as to supply 80 code to the track transformer TB of track 70 circuit 4T. Consequently, track relay TRA will follow 80 code and so will cause the signal 4 to display the "caution" indication.

The crossing control relay XRE is normally energized over a circuit which includes the front 75

contacts 52 and 53 of relay HC and the front contacts 54 and 55 of relay ATPD. Location C is therefore a starting point for the control of the highway crossing apparatus at location E. Accordingly, when the train enters track circuit 6T and deenergizes track relay TRC and decoding relay HC, the release of the latter relay will open the front contacts 52 and 53 so as to deenergize the relay XRE. This relay, in turn, will close its back contact 56 so as to initiate the operation of the highway crossing signals A6X at location E.

When the train enters the track circuit A6T, the track relay TRD and relays TPD and ATPD will all become deenergized. The opening of front contacts 54 and 55 of relay ATPD will maintain the relay XRE in its deenergized condition.

With the opening of the front contacts 36-37 and 39-40 of relay ATPD, the coded energy which had previously been supplied to track transformer TD will now be discontinued. As soon as the back contacts 36-38 and 39-41 of this relay become closed, however, uncoded energy of opposite instantaneous polarity will be fed to the primary of track transformer TD and, therefore, to the rails of track circuit 6T. Whereupon, as soon as the track circuit 6T is vacated, the uncoded energy will cause the auxiliary relay ATRC to become energized, back contact 13 of relay HC being closed at this time to cause energy to be supplied to the local winding 9 of relay ATRC. As soon as auxiliary relay ATRC becomes energized, it will close its front contacts 57 and 58 and so will complete the energizing circuit for relay XRD, which, in turn, will discontinue the operation of the highway crossing signals 6X at location D. During the time that track circuit 6T receives uncoded energy, the track relay TRC is maintained deenergized by being driven against its backstop so that signal 6 continues to remain at "stop."

When the train enters the track circuit B6T, the track relay TRE and its associated repeater relays TPE and ATPE will all become deenergized and uncoded energy will be fed to the track circuit A6T in the rear over the back contacts 26-30 and 28-31 of relay ATPE. When the track circuit A6T becomes completely vacated, the auxiliary track relay ATRD will become energized on steady energy and in so doing will close its front contacts 59 and 60, thereby closing the energizing circuit for the highway crossing control relay XRE. This relay will, in turn, open its back contact 56 to thereby discontinue the operation of the highway crossing signals A6X at location E.

When the track circuit B6T is vacated, 80 code will be fed to this track circuit over the back contact 18-20 of decoding relay HF and wires 21 and 22 to track transformer TF, as before.

This code will also be supplied to track transformers TE and TD over the line circuits in the manner previously explained in connection with the supply of 180 code. Accordingly, relay TRC at location C will follow 80 code and will cause the signal 6 to display a "caution" indication. In consequence, 180 code will be supplied over front contact 49-50 of relay HC to track transformers TC and TB. The response of relay TRA to 180 code will, of course, cause signal 4 to assume its "proceed" position.

When the train proceeds out of the block immediately in advance of location F, 80 code will be supplied to the track relay TRF which, in following this code, will cause 180 code to be supplied to the track circuits of the blocks A-C and

C-F. All of the apparatus will then be restored to the condition in which it is illustrated in the drawings.

It will be apparent from the foregoing that we have provided a signalling system in which coded energy is used for controlling wayside and cab signals and in which uncoded energy is used in the rails for performing certain additional control functions. The apparatus is further so arranged that the use of uncoded energy does not interfere with the proper safety operation of the usual code following track relay and does not decrease the foreign current protection provided by this relay.

Although we have herein shown and described only one form of apparatus embodying our invention, it is understood that various changes and modifications may be made therein within the scope of the appended claims without departing from the spirit and scope of our invention.

Having thus described our invention, what we claim is:

1. In combination with a section of railway track, means for at times supplying coded current and for at other times supplying uncoded current to the rails of said section, a code following track relay receiving energy from the rails of said section, an auxiliary track relay controlled by energy received from the track rails and designed for operation on said uncoded current but not on said coded current, a traffic controlling line circuit, means controlled by said code following track relay effective at such times for maintaining said line circuit energized and for insuring non-operation of said auxiliary relay once code following action of said code following relay has been established, and means controlled by said auxiliary track relay effective at said other times for maintaining said line circuit energized independently of the control exercised by said code following track relay.

2. In combination with a section of railway track, means for at times supplying coded current and for at other times supplying uncoded current to the rails of said section, a code following track relay receiving energy from the rails of said section, an auxiliary track relay controlled by energy received from the track rails and designed for operation on said uncoded current but not on said coded current, a decoding relay energized in response to code operation of said code following track relay, means controlled by said decoding relay for insuring non-operation of said auxiliary relay once code following action of said code following relay has been established, a traffic controlling line circuit, a front contact of said decoding relay included at said times in said line circuit, and a path around said front contact closed at said other times and including a front contact of said auxiliary track relay.

3. In combination with a section of railway track, means for at times supplying coded current and for at other times supplying uncoded current to the rails of said section, a code following track relay receiving energy from the rails of said section, an auxiliary track relay controlled by energy received from the track rails and designed for operation on said uncoded current but not on said coded current, said auxiliary track relay having a control current connected with the rails of said section and having a local element, a decoding relay energized in response to code operation of said code following track relay, means controlled by said decoding relay effective at said other times for supplying uncoded current

- to the local element of said auxiliary track relay to cause operation thereof, said last-mentioned means acting to deenergize said local element to insure non-operation of said auxiliary relay once 5 code following action of said code following relay has been established, a traffic controlling line circuit, a front contact of said decoding relay included at said times in said line circuit, and a path around said front contact closed at said 10 other times and including a front contact of said auxiliary track relay.
4. In combination with a section of railway track, means for at times supplying coded current and for at other times supplying uncoded current 15 to the rails of said section, a code following track relay receiving energy from the rails of said section, an auxiliary track relay controlled by energy received from the track rails and designed for operation on said uncoded current, a 20 repeating relay energized only in response to code operation of said code following track relay, said repeating relay when energized being effective for preventing operation of said auxiliary track relay at said times when coded current is supplied to 25 said rails, traffic controlling apparatus governed by said repeating relay and by said auxiliary track relay, and means controlled by said repeating relay when deenergized for supplying uncoded current to the rails in the rear of said 30 track section.
5. In combination with a forward and a rear section of railway track, coding means for at times supplying coded current to the rails of said forward section, a code following track relay for 35 said forward section, a repeating relay energized only in response to code operation of said code following track relay, means effective when said repeating relay is energized and including said coding means for also supplying coded current to the rails of said rear section, means effective when said repeating relay is deenergized for supplying uncoded current to the rails of said rear section, a code following track relay for said rear section, an auxiliary track relay for said rear section controlled by energy received from the track rails and designed for operation on said uncoded current, means controlled by the code following track relay for said rear section effective 45 when this relay is operating for preventing operation of said auxiliary track relay when coded current is supplied to the rails of said rear section, and traffic controlling apparatus governed by the code following track relay for said rear section and said auxiliary track relay.
6. In combination with a forward and a rear section of railway track, coding means for at times supplying coded current to the rails of said forward section, a code following track relay for 50 said forward section, a repeating relay energized only in response to code operation of said code following track relay, means effective when said repeating relay is energized and including said coding means for also supplying coded current to the rails of said rear section to control traffic entering said rear section, means effective when said repeating relay is deenergized for supplying uncoded current to the rails of said rear section, an auxiliary track relay for said rear section controlled by energy received from the track rails and designed for operation on said uncoded current, means controlled by the coded current in said rear section for preventing operation of said auxiliary track relay when coded current is supplied to the rails of said rear section, and signalling 55 apparatus controlled by said auxiliary track relay.
7. In combination with a forward and a rear section of railway track, means for at times supplying coded current and for at other times supplying uncoded current to the rails of said forward section, a code following track relay for said forward section, a decoding relay energized only in response to code operation of said code following track relay, means effective when said decoding relay is energized for supplying coded current to the rails of said rear section to control traffic entering said rear section, an auxiliary track relay for said forward section controlled by energy received from the track rails and designed for operation on said uncoded current, said decoding relay when energized being effective for preventing operation of said auxiliary track relay at said times when coded current is supplied to the rails of said forward section, and track detection apparatus controlled by said decoding relay and said auxiliary track relay.
8. In combination with a forward and a rear section of railway track, means for at times supplying the rails of both of said sections with coded current, means for at other times supplying the rails of said forward section with uncoded current, a code following track relay for each of said sections, a repeating relay for each section energized only in response to code operation of the code following track relay associated therewith, an auxiliary track relay for said forward section controlled by energy received from the track rails and designed for operation on said uncoded current, said repeating relay for the forward section when energized being effective for preventing operation of said auxiliary track relay at said times when coded current is supplied to the rails of said forward section, and traffic controlling apparatus governed by both said repeating relays and said auxiliary track relay.
9. In combination with a forward and a rear section of railway track, means for at times supplying the rails of both of said sections with coded current, means for at other times supplying the rails of said forward section with uncoded current, a code following track relay for each of said sections, a repeating relay for each section energized only in response to code operation of the respective code following track relay associated therewith, an auxiliary track relay for said forward section controlled by energy received from the track rails and designed for operation on said uncoded current but not on said coded current, means controlled by the repeating relay for said forward section for insuring non-operation of said auxiliary relay once code following action of said code following relay for the forward section has been established, a traffic controlling line circuit including a front contact of each of said repeating relays, and a path around the front contact of the repeating relay for said forward section including a front contact of said auxiliary track relay.
10. In combination with a forward and a rear section of railway track, means for normally supplying coded current to the rails of both sections, a code following track relay for each of said sections, normally inoperative signalling apparatus associated with said forward section, means effective when a train enters said rear section and including the code following relay for the rear section for initiating operation of said signalling apparatus, means effective when the train enters said forward section and including the code fol-

lowing relay for the forward section for maintaining said signalling apparatus in its operated condition during occupancy of said forward section, an auxiliary track relay for said forward section controlled by energy received from the track rails and designed for operation on said uncoded current but not on said coded current, means effective upon the entry of the train into the section immediately in advance of said forward section for supplying uncoded current to the rails of the forward section for energizing said auxiliary track relay on said uncoded current as soon as the train vacates the forward section, means controlled by the code following track relay for said forward section effective when this relay is operating for preventing hammering action of said auxiliary track relay against its backstop when coded current is effective in the rails of the forward section, and means controlled by said auxiliary track relay when energized for restoring said signalling apparatus to its normally inoperative condition.

11. In combination with a section of railway track, means for at times supplying coded current of a given relative polarity and for at other times supplying uncoded current of the reverse relative polarity to the rails of said section, a main track relay responsive to code and receiving energy from the rails of said section, a two-element auxiliary track relay having its control element energized from the rails of said section, means controlled by said main track relay for preventing energization of the local element of said auxiliary relay at said times once code following action of said main relay has been established, means effective at said other times for energizing said local element to cause pick-up of said auxiliary relay on said uncoded current, the energization of said local element being in such direction as to prevent pick-up of the auxiliary relay on code during the time required for the code following action of said main relay to be established, traffic controlling apparatus governed by said main track relay, and track detection apparatus governed by said auxiliary track relay.

12. In combination with a section of railway track, means for at times supplying coded current of a given relative polarity and for at other times supplying uncoded current of the reverse relative polarity to the rails of said section, a main track relay responsive to code and receiving energy from the rails of said section, a two-element auxiliary track relay having its control element energized from the rails of said section, means controlled by said main track relay for preventing energization of the local element of said auxiliary relay at said times once code following action of said main relay has been established, means effective at said other times for energizing said local element to cause pick-up of said auxiliary relay on said uncoded current, the energization of said local element being in such direction as to prevent pick-up of the auxiliary relay on code during the time required for the code following action of said main relay to be established, and traffic controlling apparatus governed by said main track relay and said auxiliary track relay.

13. In combination with a section of railway track, means for at times supplying coded current of a given relative polarity and for at other

times supplying uncoded current of the reverse relative polarity to the rails of said section, a main track relay responsive to code and receiving energy from the rails of said section, a two-element auxiliary track relay having its control element energized from the rails of said section, means controlled by said main track relay for preventing energization of the local element of said auxiliary relay at said times once code following action of said main relay has been established, means effective at said other times for energizing said local element to cause pick-up of said auxiliary relay on said uncoded current, the energization of said local element being in such direction as to prevent pick-up of the auxiliary relay on code during the time required for the code following action of said main relay to be established, and a traffic controlling line circuit governed by said main track relay and said auxiliary track relay.

14. In combination with a section of railway track, means for at times supplying coded current and for at other times supplying uncoded current to the rails of said section, a main track relay responsive to code and receiving energy from the rails of said section, a two-element auxiliary track relay having its control element energized from the rails of said section, means controlled by said main track relay for preventing energization of the local element of said auxiliary relay at said times once code following action of said main relay has been established, means effective at said other times for energizing said local element to cause pick-up of said auxiliary relay on said uncoded current, the energization of said local element being in such direction as to prevent pick-up of the auxiliary relay on code during the time required for the code following action of said main relay to be established, a highway crossing control relay, a first circuit for said highway crossing control relay governed by said main track relay, and a second circuit for said highway crossing control relay governed by said auxiliary track relay.

15. In combination with a forward and a rear section of railway track, means for normally supplying coded current to the rails of both sections, a main track relay for said rear section responsive to code, means effective when a train enters said forward section for supplying uncoded current of reverse relative polarity with respect to said coded current to the rails of said rear section, a two-element auxiliary track relay having its control element energized from the rails of said rear section, means controlled by said main track relay for preventing energization of the local element of said auxiliary relay when code is supplied to the rails of said rear section once code following action of said main relay has been established, means effective when uncoded current is supplied to said rear section for energizing said local element to cause pick-up of said auxiliary relay on said uncoded current, the energization of said local element being in such direction as to prevent pick-up of the auxiliary relay on code during the time required for the code following action of said main relay to be established, train governing apparatus controlled by said main track relay, and track detection apparatus controlled by said auxiliary track relay.
